LLP(57) **CLAIM**

We claim the ornamental design for a perforated collapsible box, as shown and described.

DESCRIPTION

FIG. 1 is a front perspective view of the claimed design.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The features shown in broken lines form no part of the claimed design, such as the broken lines denoting lines of weakness shown in FIGS. 1, 2, 3, 5, and 6 and the tape strips shown in FIGS. 1-3 and 6-7.
